[57] CLAIM

The ornamental design for a bendable toy, as shown and described.

DESCRIPTION

FIG. 1 is a perspective view of the bendable toy embodying the design of the present invention;
FIG. 2 is a front elevational view thereof;
FIG. 3 is a rear elevational view thereof;
FIG. 4 is a side elevational view thereof, the side opposite being a mirror image of the side shown in FIG. 4; and,
FIG. 5 is a top plan view thereof, the bottom view being a mirror image of the top view shown in FIG. 5.

FIG. 1.

FIG. 2.

FIG. 3.

FIG. 4.

FIG. 5.
